CANDY BOX CRADLE SHAPER AND BOX FEEDER

George C. Sparks, Chadds Ford, Pa.

Application September 7, 1951, Serial No. 245,583

7 Claims. (Cl. 53—69)

1

My invention relates to a new and useful candy box cradle shaper and box feeder and has for one of its objects to produce a semi-automatic apparatus to deliver the uppermost one of a column of nested boxes to a location adjacent a shaper which turns up the ends of a supporting cradle about an article as such article is placed on the body panel of the cradle and forced downwardly to depress a portion of the shaper.

Another object of the invention is to produce a device of the kind mentioned including a hollow standard to receive and hold a column of nested boxes for delivery at the top of said standard, step by step, each time the then upper one is removed, said step by step delivery being accomplished by a spring actuated ascending platform within the standard, on which the column of boxes is mounted, and resilient stop fingers at the upper end of said standard to temporarily engage the upper edges of the sides of the uppermost box in the column of boxes.

Another object of this invention is to produce an apparatus of the character herein set forth including the elements of a shaper or former for an article supporting cradle to be assembled in a box, the shaper or former comprised of a shelf supported on a side of the hollow standard and carrying upright brackets on which are loosely pivoted parts of a hinge jointed seat, spring actuated in one direction to normally lie in a substantially horizontal plane and capable of being manually depressed for folding a cradle about an article resting on a part of said cradle which is imposed on said seat.

The apparatus is particularly adapted for use by small candy distributors and especially those who pack limited quantities of articles, such as Easter eggs, at various holiday seasons. Therefore, a further object of the present invention is to produce a device which will be relatively inexpensive to manufacture, strong and durable and highly efficient in operation and which, when in use, will expedite the packing operations and reduce labor costs.

A still further object of this invention is to combine a box feeding mechanism cooperatively with a shaping mechanism for box inserts, which cradle fragile articles when packed, whereby an operator can first cause the ends of a suitable cradle insert to be folded onto an article by depressing a portion of the shaping mechanism through the medium of said article, then inserting the article with its cradle in an adjacent box and, finally, removing the box with its contents from the feeding mechanism by flexing the sides

2

of said box, said feeding mechanism thereafter positioning another box for subsequent packing.

With the above and other objects in view this invention consists of the details of construction and combination of elements hereinafter set forth and then designated by the claims.

In order that those skilled in the art to which this invention appertains may understand how to make and use the same I will describe its construction in detail, referring by numerals to the accompanying drawings forming a part hereof, in which:

Fig. 1 is a perspective view of a candy box cradle shaper and box feeder constructed in accordance with my invention.

Fig. 2 is a fragmentary front elevation of the upper portion thereof showing a cradle and an article, such as an Easter egg, in dotted lines on the shaper portion of the device.

Fig. 3 is a similar view illustrating the shaper seat depressed with the ends of the cradle folded over the ends of the article.

Fig. 4 also is a similar view of the upper part of the box feeder only showing the cradle and the supported article as they are inserted in the uppermost box.

Fig. 5 is a vertical or longitudinal sectional view of the apparatus through the upright standard of the box feeder mechanism with the elevator platform and spring actuated reel in elevation and a lowered position of said platform shown in dotted lines.

Fig. 6 is an enlarged fragmentary sectional view on the line 6—6 of Fig. 7.

Fig. 8 is a fragmentary section on the line 8—8 of Fig. 7.

Fig. 9 is a plan view of one type of cradle prior to being folded.

Fig. 10 is a perspective view of another type of cradle partially folded.

In carrying out my invention as herein embodied 15 represents any suitable base on which is mounted a hollow upright standard 16 having an open upper end and a partially open front, the latter for easy access to the interior of said standard throughout its entire height. This standard essentially includes a back wall 17, side walls 18, at right angles to said back wall, and inturned relatively narrow flanges 19 projecting towards each other but spaced apart to provide the front opening.

Within the standard is slidably mounted a platform 20 for ascent and descent and said platform is prevented from tilting forwardly by a pendant guide bracket 21 riding on the inside

surface of the back wall 17. The platform is normally urged upwardly and, therefore, elevated, under certain conditions, by means of an ordinary spring actuated window sash lifter 22 including a casing 23 mounted on the exterior of the back wall 17 of the standard and housing a spring actuated reel 24 which winds up a flexible strap 25, preferably of metal, the free end of which projects through an aperture 26 in said back wall 17 and is fastened to the platform 20.

On the platform within the hollow standard is mounted a column of nested boxes 27 each including a body with walls diverging from the lower end to the upper end, foldable side flaps 28 and a foldable cover 29. As the column of boxes is elevated, the side flaps of the boxes approaching the top of the standard are deflected inwardly, with relation to a box structure, by the beveled lower ends of the deflector plates 30 mounted on the inner surfaces of the side walls of the standard at the upper ends thereof. The flaps are then retained in the deflected positions by the prolonged holding surfaces of the deflector plates, which extend to the extreme upper end of the standard, until the upper edges of said flaps engage the bites of the hook portions of the stop fingers 31 secured to the side walls of the standard. The hook portions of said stop fingers project above the upper end of the standard whereby the side flaps of the uppermost box of the column are exposed to be readily grasped by an operator. Said stop fingers are formed, preferably, of stiff resilient metal.

On the exterior of one side of the standard is a horizontal shelf 32 which may be braced by struts 33. A pair of opposed spaced upright brackets 34 are mounted on top of the shelf 32. These supporting brackets 34 are of identical construction and are U-shaped in horizontal cross section providing parallel sides and a back having its upper end cut out, as at 35.

A hinged rest 36 for shaping the article supporting cradle is pivoted between the vertical brackets 34 and said rest includes a center plate or leaf 37 and end plates or leaves 38, one hinged to each end of said center plate or leaf. From the sides of the end leaves 38, in particular, project the perpendicular legs 39 which telescope over the exteriors of the sides of their respective vertical brackets 34. Said legs have slots 40 which are angular to the planes and converge towards the outer ends of their respective end leaves.

An axle 41 is projected through the sides of each vertical bracket 34 and the slots 40 in the legs 39 of the associated end leaf of the hinged rest 36 thereby pivotally connecting the ends of said hinged rest to the vertical brackets with the center leaf 37 suspended and capable of being projected downwardly between said brackets.

The rest 36 is normally maintained in a substantially horizontal plane, although the end leaves may be tilted as shown in Fig. 6, by a spring 42 which urges the center leaf 37 upwardly or outwardly. For purposes of illustration, the spring is shown as encircling a rod 43, secured to the underside of the center leaf and slidably projecting through a sleeve 44 and the shelf 32 on which said sleeve is mounted, the upper end of the latter having a socket 45 to receive the lower end of said spring.

In Fig. 10 I have shown one type of article supporting cradle 46 which is also illustrated in dotted lines in Figs. 2, 3 and 4. This particular

type of cradle includes a web 47 with end wings 48 defined by weakened fold lines 49. The end wings 48 are provided with perpendicular end and side flanges 50 and 51, respectively to space the end wings from contiguous walls of the box in which the cradle is assembled. Also each of said end wings has an aperture 52 to receive the ends of an article mounted on the web of the cradle.

The other type of cradle 46a depicted in Fig. 9 includes a web 47a with end wings 48a defined by the weakened fold lines 49a and having side flanges 51a which are foldable perpendicular to their respective end wings which latter also have apertures 52a to receive the ends of an article to be packed.

When the cradle, as 46, is placed on the shaper rest 36, the web 47 and the end wings 48 are superimposed upon the center leaf 37 and the end leaves 38, respectively, with the apertures 52 in said end wings in line with openings 53, one provided in each leaf so that as the cradle wings and the end leaves of the rest are folded to embrace the ends of an article 54, Figs. 2, 3 and 4, said ends of the article may project through the leaf opening to prevent damage to or marring of said article, especially the ends thereof.

In actual practice, a number of the boxes 27 are nested and inserted in the top of the hollow standard in columnar arrangement with the bottom of the lowermost box resting on the elevator platform 20. In order to nest the boxes the foldable covers are turned back which leaves the upper ends of said boxes open. The platform 20 is then propelled downwardly against the action of the spring actuated reel 24 until the side flaps 28 of the uppermost box in the column pass the hook portions of the stop fingers 31. The platform 20 is then released and the spring reel will elevate said platform until the flaps of the uppermost box enter the bites of said stop fingers at which time the entire column of boxes will be arrested. The boxes are now ready to be packed.

It is desired that each article be prevented from shifting about in its box; therefore a supporting cradle 46, 46a is employed to encircle the ends of the article and support the latter out of contact with the sides, ends, top and bottom of the box. To expedite the packing operations a cradle is imposed upon the shaping rest 36, Fig. 2, with the web and wings of said cradle substantially flat while the flanges thereof project over the side edges and, in some instances, the outer end edges of the rest. An article 54 is next placed on the flat cradle, centrally thereof, and pushed downwardly to depress the center leaf of the shaping rest against the action of the spring 42. This function will cause the end leaves of said shaping rest to rotate inwardly and move downwardly, because of the loose or slidable pivotal connection of said end leaves with their respective axles, to fold the end wings of the cradle over the ends of the article, as shown in Fig. 3.

The cradle, with the article therein, is then lifted from the shaping rest, which will return to its normal position as pressure thereon is relieved, due to expansion of the spring, and said cradle and article are inserted in the uppermost box within the standard, Fig. 4. Finally, the side flaps 28 of said uppermost box are disengaged from the stop fingers 31 by flexing or folding said flaps inwardly towards each other and, if necessary, simultaneously depressing the column of boxes. This will release the uppermost box so that it can be withdrawn from the

column of boxes and removed from the hollow standard. As said uppermost box is removed, the column of boxes will be elevated, by the action of the spring reel on the platform 20, until the side flaps of the succeeding box engage the stop fingers. These operations continue in proper sequence until all of the articles are packed.

From the foregoing it will be apparent that I have produced an exceedingly simple, inexpensive, strong and durable portable apparatus for feeding boxes and shaping supporting cradles about articles to be packed in the boxes thus adapting it to use by concerns which pack small amounts of goods and certain periods in contradistinction to those that pack large quantities substantially continuously. When not in use this apparatus can be stored in any convenient locality.

Of course I do not wish to be limited to the exact details of construction herein shown and described as these may be varied within the scope of the appended claims without departing from the spirit of my invention.

Having described my invention what I claim as new and useful is:

1. A candy box cradle shaper and box feeder comprising a hollow upright standard open at the top, a platform in said standard to support a column of nested boxes, the upper edges of which are capable of being flexed inwardly, spring actuated mechanism to urge said platform upwardly for elevating the boxes, stop fingers to be engaged by edges of the uppermost box in the column to temporarily arrest the upward movements of the boxes and platform, the uppermost box being disengaged from the fingers for removal from the column by flexing portions of said uppermost box and the removal thereof causing the column of boxes to move upwardly until the edges of the succeeding box engage said fingers, a shelf on one side of the standard adjacent the upper end thereof, and an article supporting cradle shaper on said shelf, said shaper consisting of two spaced upright brackets secured to the top of said shelf, a three-piece hinged rest having the end pieces loosely pivotally connected to the brackets with the center piece capable of depression between said brackets to swingingly move the end pieces generally inwardly for folding apertured end leaves of a cradle over the ends of an article resting on a central web of the cradle prior to insertion in the uppermost box of the column of boxes, the depression of the center piece of the rest being accomplished through pressure applied to the article, and a spring to retract the rest.

2. The structure according to claim 1 in combination with deflector plates on opposite sides of the interior of the standard at the upper end thereof, the lower edges of said deflector plates being beveled.

3. A portable candy box cradle shaper and box feeder comprising a base, a hollow upright standard open at the top and provided with an opening in the front from top to bottom thereof and of less width than said front, a platform mounted in said standard for vertical movements, a spring actuated reel mounted on the exterior of the back of the standard and functioning to wind up a metal strap passing through an opening in said back and attached to said platform for constantly urging the latter upwardly, deflector plates having beveled lower ends and mounted on opposite sides of the interior of the standard at the upper end of the latter, stop fingers se-

cured to opposite sides of the standard and having inturned hook portions located above the upper end of said deflector plates, a shelf on the exterior of one side of the standard adjacent the upper end thereof, spaced opposed brackets projecting upwardly from the shelf, end pieces of a folding rest pivotally and slidably connected to said brackets, a center piece of the folding rest hingedly connected to both of the end pieces and adapted to be depressed for swinging the end pieces inwardly, said end pieces having openings to accommodate the ends of an article as the center piece is depressed and said end pieces are swung inwardly, and means to urge the center piece upwardly and thereby swing the end pieces outwardly.

4. In a device of the kind described, a hollow upright standard mounted on a base and open at the top as well as partially open in the front entire height thereof, a platform slideable vertically within said standard to support a column of nested boxes having flexible upper edges, a spring actuated mechanism to urge said platform upwardly for elevating the boxes, deflector plates in the standard at the upper end thereof to center the boxes during the final upward movement thereof, stop fingers secured to opposite sides of the standard and having inturned hook portions located above the upper end of said standard in line with the exposed faces of said deflector plates to engage the upper edges of a succeeding box as the sides of the preceding box are flexed to disengage them from the stop fingers and said preceding box is removed, and means on a side of the standard adjacent the upper end thereof for folding an article supporting cradle to be inserted in said preceding box prior to removal from the standard.

5. The structure according to claim 4, in combination with a pendant guide bracket secured to the underside of the platform and engaging a wall of the standard to prevent forward tilting of said platform.

6. In a device of the character described, a standard through which boxes are fed step by step each time an uppermost one is removed, a shelf on the exterior of one side adjacent the upper end of said standard, two upright brackets in spaced relation on top of said shelf, a sleeve midway between said brackets and projecting through the shelf, a jointed rest comprised of a center leaf and end leaves hinged to said center leaf at opposite ends thereof, said leaves having legs perpendicular thereto with slots angular to the planes of said end leaves, means passing through the upright brackets and said sleeve to pivotally and slidably mount the end leaves of the rest whereby said end leaves may be swung inwardly as the center leaf is depressed, a rod secured to the underside of said center leaf and slidably mounted in said sleeve, and a coil spring about the upper part of the rod between the sleeve and center leaf of the rest to urge the latter upwardly for returning said rest to a substantially horizontal position after each depression of the center leaf, the depression of said center leaf, while a foldable cradle and article is disposed on the rest, folding the ends of the cradle upon the ends of the article.

7. The structure of claim 6 wherein the end leaves of the rest have openings whereby apertured cradle ends may be projected over the ends of the article on the cradle.

GEORGE C. SPARKS.
